UTILITY BURNER FOR PAINT OR THE LIKE

Alfred E. D'Harlingue, St. Louis, Mo.

Application October 3, 1949, Serial No. 5,276

Term of patent 14 years

(Cl. D93—4)

To all whom it may concern:

Be it known that I, Alfred E. D'Harlingue, a citizen of the United States, residing at the city of St. Louis, in the State of Missouri, have invented a new, original, and ornamental Design for a Utility Burner for Paint or the like, of which the following is a specification, reference being had to the accompanying drawing, forming a part hereof.

Figure 1 is a view in side elevation of a utility burner for paint or the like, showing my new design.

Figure 2 is a view in front elevation of the same.

Figure 3 is a plan view from the underside of the same.

Figure 4 is a perspective view of the same.

I claim:

The ornamental design for a utility burner for paint or the like, as shown.

ALFRED E. D'HARLINGUE.
